UNITED STATES PATENT OFFICE.

ROBERT E. McGAHEY, OF ALEXANDRIA, VIRGINIA.

RAILWAY-TRACK SKATE.

Application filed February 27, 1925. Serial No. 12,104.

To all whom it may concern:

Be it known that I, ROBERT E. McGAHEY, a citizen of the United States, residing at Alexandria, in the State of Virginia, have 5 invented certain new and useful Improvements in Railway-Track Skates, of which the following is a specification.

This invention relates to railway track skates and has for an object to provide a 10 device of the general class adapted to be placed upon a railway rail upon and against which the wheel of a car impinges in motion and which is adapted to slide along on the rail under such wheel for the purpose of 15 stopping the car by the frictional engagement of the skate with the rail.

A further object of the invention is to provide such a track skate which, when in 20 operative position, is free to slide along the rail to an unlimited distance and, when in normal location, may be raised upon and removed from operating position on the rail, and to operate either manually at the location 25 of the skate or from a distance by power transmission.

A further object of the invention is to provide an organization attached to a rail embodying some power means as for instance a pneumatic cylinder by which power 30 may, when desired, be applied to operate the skate with a skate associated with the installation in position, when removed from the rail, to be locked against displacement and, when placed upon the rail, free to leave 35 the organization and slide an unlimited distance along and upon the rail.

A further object of the invention is to provide a track skate of the type mentioned with improved means associated with its location 40 at the rail enabling a distant operator to throw the skate upon or off the rail while permitting the actuation of the skate in either direction manually at the location.

With these and other objects in view, the 45 invention comprises certain novel parts, elements, units, combinations, interactions, mechanical movements and functions as disclosed in the drawings, together with mechanical and functional equivalents thereof 50 as will be hereinafter more fully described and claimed.

In the drawings:

Figure 1 is a view in elevation of the 55 track skate and operating means, the skate being shown in end elevation and the oper-

ating means in side elevation and the rail in transverse section.

Figure 2 is a top plan view of the base to which the structure is applied with the 60 skate removed.

Figure 3 is a view of the skate in end elevation.

Figure 4 is a view of the skate in side elevation, a part being broken away to show 65 the sand pocket.

Figure 5 is a top plan view of the skate.

Figure 6 is a plan view of the skate operating link.

Figure 7 is a view of the skate operating 70 link in side elevation.

Figure 8 is a plan view of the skate in position upon a rail and with its associated parts.

Figure 9 is a view in side elevation of one 75 of the bearings for supporting the skate.

Figure 10 is a top plan view of the bearing which is shown in side elevation at Figure 9.

Figure 11 is a view in side elevation of another bearing for the skate.

Figure 12 is a view in top plan of the bearing shown in elevation at Figure 11.

It is well known that appliances are already in use known as track skates or track skids and by various other names which are seated manually upon a rail in position so that the front wheel of a car moving toward the positioned skate will ride upon the skate and coming in contact with an abutment the continued momentum of the car will cause 85 the skate to slide along the rail supporting the wheel and will stop the car by the frictional engagement of the skate upon the rail.

The present invention comprises a skate 90 having an elongated body 20 with flanges 21 and 22 positioned to sit upon the head 23 of the rail with the flanges upon the opposite side. The body 20 provides an abutment 24 against which the wheel of the car 95 in motion engages, a hump 25 also being preferably provided to prevent rebound. A shoulder 26 in the present invention is provided in such position that the car while resting upon the body 20 will engage against 100 this shoulder and tend to tilt the skate so that the nose or point 27 will dig into the rail or at least will increase the frictional engagement between the skate and the rail.

For the purpose also of increasing such 110

frictional engagement, an opening 28, called a sand pocket, is formed in the skate having a perforated bottom 29 which may and preferably will be a block of wood with 5 holes therein and closed by a plug 30 which likewise may and preferably will be a block of wood. When the skate is in upright position as shown at Figures 3 and 4, and is moved forcibly and slidably along the rail, 10 the sand from the pocket 28 will sift through the perforations of the plug 29 and prevent undue slippage of the skate upon the rail which precaution is especially desirable for wet weather use.

15 To handle the skate under manual conditions, a handle 31 is provided by which the skate as an entirety may be moved or raised.

The present invention embodies means for 20 locating this skate at a definite position relative to the rail and to provide means whereby the skate may be placed upon or removed from the rail by an operator at a distant point, as for instance in a switch tower. 25 This construction comprises a base 32 which is preferably bolted to the flange 33 of the rail as indicated at 34, it being understood, of course, that the manner of bolting may be varied as found desirable. 30 To the base 32 a bearing 35 is preferably secured permanently as by welding the part 36 and said bearing is also preferably bolted to the web of the rail as at 37. This adds 35 additional engagement between the base 32 and the rail. This bearing 35 is preferably adjacent one side of the base 32 and a second bearing 38 is secured in a position adjacent the opposite side of the base. It is not the intent that said bearing 38 shall be permanently secured to the base but is bolted 40 at 39 to the rail. The bearings 35 and 38 are properly spaced apart, the former to engage the section 39 and the latter the section 40 of a trunnion formed upon the side 45 of the skate, preferably integral therewith and joined by means of a web 41. This trunnion embodying the sections 39 and 40 is properly proportioned to be engaged by the bearings 35 and 38, the end 40 being inserted slidably into the opening 42 by sliding first through the key hole slot 43 in the bearing 35. When the skate has been 50 slidably moved along the rail so that the two sections 39 and 40 are properly seated in the bearings 35 and 38, the skate as an 55 entirety may be tilted over off from the rail support by the bearings 35 and 38. Such tilting may be accomplished manually by 60 engaging the handle 31 but means is provided for operating the skate by power, 65 preferably from a distant point, such power means being shown conventionally by the cylinder 44. This cylinder 44 has a piston rod 45 extending outwardly therefrom, pivotally connected with a link 46. The link 46

has a right angled bend or finger 47 which engages in the opening 48 of the arm 49 which is rigidly connected and preferably integral with the trunnion and other parts of the skate structure. The finger 47 is 70 merely inserted in the opening 48 and is not in any way secured or fastened therein, so that, when the skate is raised to the position shown in full lines at Figure 1, it is free to slide by sliding the trunnion out of 75 the opening 42 of the bearing 38 and through the opening 43 of the bearing 35, similarly out of engagement with the finger 47, so that the skate as an entirety is free to leave 80 its association with the operating means and slide along under the impact of the car engaged thereon. Merely for the purpose of preventing side stress or strain upon the link 46, abutments or lugs 49' and 50 are 85 rigidly secured to the base 32 so that the link operates between these lugs and is not subjected to side strain or breaking stress in case of any binding between the finger 47 and arm 49 as the skate leaves its position 90 relative to the base 32.

Assuming that the power means 44 is a 95 pneumatic cylinder, it is obvious that its actuation may be controlled from a distant point as for instance a switch tower, the same being true, of course, if the part 44 represents or is embodied in any other type of power means as for instance electric means, it being understood that the part 44 is merely a conventional showing of any desired power means.

In operation, the skate will normally lie alongside the rail in the position shown in dotted lines at Figure 1. It is intended that this skate shall be used at such locations as make it necessary or desirable at times to 105 stop cars moving under their own momentum, either in switching or for other purposes. It will find its greatest utility in switching cars on a gravity track but is in no way limited thereto. Assuming, however, its use on such gravity track, it will, as noted, lie alongside the rail until a car starts down the incline and it is desired to stop the car in its progress. The switchman in the tower, noting the position of the car, 110 will operate the proper mechanical devices for energizing the power means, as for instance admitting air to the pneumatic cylinder, which will cause the piston through the medium of the link to lift the skate from the inclined or inoperative position and place it upon the top of the rail. If the car proceeds to this point and engages upon the skate, the skate will disengage itself wholly and entirely from all association 115 with the operating means and will slide along the rail so far and for such length of time as the momentum of the car impels.

After the car has been removed from the 120 skate, the skate is manually carried back to 125

position and being set down upon the top of the rail is slidably inserted first through the bearing 35 and then the end of the trunnion into the bearing 38 with, of course, the 5 finger 48 located in the opening 38 of the arm 49. The dropping down of the skate to normal or inoperative position locks it thoroughly against sliding movement as the web 41 engages against the bearings 35 and 10 38 in both directions and by reason of the key hole shape of the opening 43 in the bearing 35 the skate bodily can not be lifted out of such position. It is released by and only by a sliding movement when and only when the 15 skate is in erect position upon the top of the rail. At all other times, it is locked against movement in all directions.

What I claim to be new is:

1. A track skate embodying a base rigidly 20 connected with a rail, a skate member hinged to the base and adapted to assume erect positions upon the rail and inoperative positions at the side of the rail, means locking the skate against displacement when 25 in inclined position, said means permitting the skate to slidably move out of association with the base when in erect position.

2. A track skate embodying a base rigidly 30 connected with the rail, a skate member pivoted to the base, and power means adapted to raise the skate into operative position upon the rail and remove it to inoperative position at the side of the rail.

3. A track skate organization comprising 35 a base rigidly connected with a rail, a skate

member pivoted to the rail and adapted to occupy an erect position upon the top of the rail and an inclined position at the side of the rail, power means carried by the base for moving the skate in either direction relative to the rail, and means hinging the skate to the base serving to lock the skate against displacement when in inclined position and to permit its removal from association with the base by sliding longitudinally when in 45 erect position.

4. A track skate organization comprising a base rigidly secured to a rail, a skate body and means hinging the skate body to the base, providing for movement of the skate 50 body from erect position upon the top of the rail to inclined position at the side of the rail, said means locking the body against displacement when in inclined position, and allowing for the longitudinal sliding disengagement of the body from the base when 55 in erect position.

5. A track skate organization comprising a body having an elongated part proportioned for supporting a car wheel and an 60 abutment against which the wheel is located, a shoulder outstanding from the abutment against which the wheel impinges, and a sharpened nose at the forward end of the body positioned to additionally frictionally engage the rail from the augmented pressure of the car wheel against the shoulder.

In testimony whereof I affix my signature.

ROBERT E. McGAHEY.
